CIGARETTE PACKAGE HOLDER OR SIMILAR ARTICLE

Mitchell A. Touart, Jr., Pensacola, Fla.

Application February 28, 1952, Serial No. 18,708

Term of patent 7 years

(Cl. D85—2)

To all whom it may concern:

Be it known that I, Mitchell A. Touart, Jr., a citizen of the United States, residing at Pensacola, Florida, have invented a new, original, and ornamental Design for a Cigarette Package Holder or Similar Article, of which the following is a specification, reference being had to the accompanying drawing, forming a part hereof.

Fig. 1 is a front perspective view of a cigarette package holder or similar article showing my new design; and

Fig. 2 is a rear perspective view thereof.

I claim:

The ornamental design for a cigarette package holder or similar article, substantially as shown.

MITCHELL A. TOUART, JR.
